GARMENT HANGER

Comer Warren and Victor W. Silverman,
Detroit, Mich.

Application January 31, 1947, Serial No. 725,608

4 Claims. (Cl. 223—89)

1

This invention relates to garment hangers and, in particular, it relates to a folding type of garment hanger. More particularly, the invention relates to a garment hanger which is foldable, at a plurality of joints, into a compact unit.

It is understood that, heretofore, certain coat or garment hangers have been devised so as to constitute a collapsible hanger. The present invention, however, comprises a collapsible or foldable hanger which may be extended to constitute a full size hanger in combination with a stability and rigidity usually associated only with conventional non-foldable types of hangers. In general, our invention comprises a foldable garment hanger which includes, in addition to the shoulder supporting members of the hanger, a horizontal member adapted for maintaining the shoulder portions in a fixed relative position. Furthermore, the horizontal member is adaptable to be locked in position, thereby rendering the assembly non-collapsible. Still further, the hanger of our invention is constructed so that it may be readily formed of sheet metal or plastic compositions.

It is, therefore, among the objects of our invention to provide a garment hanger which is collapsible and which may be folded into a relatively small compact unit; to provide a hanger of the collapsible type which may be locked in extended position; to provide a hanger of the collapsible type which includes a horizontal member extending across the base of the hanger, thus providing additional support for accessory garments; to provide a hanger of the collapsible type which may be readily formed of sheet metal or plastic composition; to provide a hanger of the collapsible type which is substantially rigid and serviceable when in extended position; and, to provide a hanger of the collapsible type which may be manufactured efficiently and economically.

These and other objects and advantages will appear more fully in the following detailed description when considered in connection with the accompanying drawing, in which:

Figure 1 is a front elevational view of a hanger of our invention illustrated in extended position;

Figure 2 is a front view of the hanger, partly in section, and partly in collapsed position;

Figure 3 is an elevational view of the hanger in fully folded position;

Figure 4 is a transverse view of the hanger, in section, taken along lines IV—IV of Figure 3; and

Figure 5 is a front view in section, of a portion of a hanger, positioned as in Figure 2, and illustrating a modified form of our invention.

2

With reference to the drawing and, in particular, to Figure 1, we show an embodiment of our invention in the form of a coat or garment hanger. In general, the invention comprises a pair of shoulder members 1 and 2, the cross-section of which is U-shape in formation. One end of the shoulder member 2 fits within the corresponding end of the shoulder member 1. An aperture 3 is formed through both associated ends 10 of the shoulder members 1 and 2, and the body of a wire hook 4 passes through the opening 3 and is riveted at the opposite side of the shoulder members so as to pivotally connect these members 1 and 2 together.

15 The opposite ends of the shoulder members 1 and 2 are each provided with apertures 5 and 6, respectively, which serve to support rivet pins 7 and 8, respectively. Pivotally associated with the pin 7 is a horizontal member 9 which is U-shaped in cross-sectional formation. The length of the horizontal member 9 is approximately one-half the distance of the shoulder to shoulder distance as determined by the extended portions of the shoulder members 1 and 2. A somewhat similar member 10 is associated with the pivot pin 8 connected to the outer portion of the shoulder member 2. An enlarged portion 11 of the horizontal member 10 fits within a corresponding enlarged portion 12 of the horizontal member 9.

20 The members 9 and 10 are joined together by means of a pin 13 fastened to and extending across the enlarged portion 12 of the member 9. A slot 14 is formed through the walls of the enlarged portion 11 of the member 10 and is adaptable for sliding engagement with the pin 13. The purpose of the slot 14 is to permit folding of the horizontal members 9 and 10 notwithstanding the pivoted association of these members with the shoulder members 1 and 2.

25 Another function of the slot 14 is to permit axial movement of the horizontal member 10 relative to the horizontal member 9. The member 9 adjacent to its enlarged portion 12 is provided with a slot 15 which, when the members 9 and 10 are pulled axially outward, enables the members 9 and 10 to be pivoted about the pin 13. This is shown, in particular, in Figure 2. How-

ever, when it is desirable to lock the hanger in its distended position, the horizontal members 9 and 10 are moved axially toward each other with the result that the upper surface 16 of the member 10 engages with the underside of the upper surface 17 of the member 9, thus preventing any pivotal movement between the members 9 and 10. This condition, in effect, locks the horizontal members 9 and 10 together and forms a substan-

tially rigid unit of all of the members 1, 2, 9 and 10.

In order to provide additional length to the hanger, we provide extension members 18 and 19 supported by the pivot pins 7 and 8, respectively. These extension members are likewise U-shape in formation. These extension members 18 and 19 include inwardly projecting portions 20 and 21 which may rest against the under surface of the horizontal members 9 and 10, respectively. When in such an extended position, the extension members 18 and 19 are capable of supporting a proper load applied to the upper side of such members. Slots or depressions 22 and 23 may be formed in the extension members 18 and 19, respectively, as an additional retaining means for supporting garments.

Preferably, the hanger is formed of sheet metal such as steel or aluminum. The construction is of such a nature that it may also be formed of various conventional plastic compositions.

Figure 1 illustrates the hanger in its fully extended and locked position. When it is desired to fold the hanger, it is merely necessary to pull the members 9 and 10 outwardly in an axial direction so that the pin 13 slides to the opposite end of the slot 14. When this occurs, the members 9 and 10 may be pivoted about the pin 13, while at the same time the outer portions of the shoulder members 1 and 2 may be drawn together. This condition of partial folding is illustrated in Figure 2. It will be noted that the U-shaped section of the horizontal member 9 is of smaller dimensions than the shoulder member 1, thus permitting the member 9 to be pivotally moved completely within the member 1.

A similar association takes place with the members 10 and 2. Upon complete folding of the members 1 and 2, as shown in Figure 3, the members lie in parallel relationship. The extension members 18 and 19 are formed of a U-shaped section slightly larger than the sections of the members 1 and 2, to permit the extension members to be folded independently back over the shoulder members 1 and 2. To complete the folding operation, the hook 4 is also pivoted downwardly so that the hook lies flat against the members 1 and 2. The entire folding operation may be accomplished quickly and easily to form a compact and neat unit, as shown in Figure 3.

Figure 5, illustrates a modified form of our invention in which a pair of shoulder members 24 and 25 formed of inverted U-shaped members are joined together with a pivot pin 26. A hook 27 is fastened to the pin 26 at a point midway between the ends of the pin. The arm 24 is provided with a slot 28, and the arm 25 is similarly provided with a slot 29. Otherwise, the arms 24 and 25 are similar in all respects to the arms 1 and 2, as shown in Figure 2. The purpose of the slots 28 and 29 is to permit the hook 27 to be pivoted about the pin 26 and folded inwardly so that the hook will lie in a position, as shown in Figure 3, except that the hook will lie within the side flanges of the U-shaped members instead of on the outside thereof, as shown in Figure 3. The purpose of positioning the hook in this manner is to permit a central suspension point upon which the hanger is more uniformly balanced. Also, by folding the hook in this manner it is almost completely encased when the hanger is in folded position, thus constituting an even more compact unit.

Horizontal members 30 and 31, which correspond with the members 9 and 10 of Figure 2, 75

are also provided with slots 32 and 33, respectively, of a length and width sufficient to provide clearance for permitting the hook 27 to be folded inwardly. The slots 28 and 29 in the arms 24 and 25, respectively, are also of a width and length to permit passage of the hook 27 therethrough when it is desired to move the hook into its folded position.

As thus shown and described, it is believed apparent that we have provided a novel garment hanger having all of the requirements of a standard size sturdy hanger, while at the same time being capable of pivotally changing its outer dimensions into a compact unit readily adaptable for transportation in a suit case, or in the pocket of a potential user.

While we have shown and described a preferred embodiment of our invention it is to be understood that it is subject to those modifications which appear obviously within the spirit of our invention and as appearing in the scope of the appended claims.

Having thus described our invention, what we claim and desire to protect by Letters Patent is:

1. A foldable garment hanger comprising a pair of arms pivotally joined together at each of one of their ends, supporting members pivotally joined to each of the arms at their opposite ends, and a pin extending through the opposite end of one of the supporting members, the other supporting member having a slot engageable with said pin, an overhanging portion on one supporting member for engagement with the other supporting member, said portion having a slot through which the end of the other supporting member may extend, the relationship of the pin and said first named slot being such that when the supporting members are axially moved toward each other the adjacent ends of the supporting members overlap each other to the extent that pivotal movement of the supporting members about the pin is prevented by the overhanging portion, whereby the supporting members are pivotally joined together while permitting limited axial movement relative to each other of the supporting members when in horizontal alignment.

2. A foldable garment hanger comprising a pair of inverted U-shaped arms the end of one of which fits within the end of the other, means for pivoting the fitted ends together, a pair of inverted U-shaped members of lesser cross-sectional dimensions than the dimensions of said arms having their adjacent ends pivotally connected together and with their opposite ends pivotally joined with the free ends of said arms, and means for locking the said members in horizontal alignment, said means comprising a pin carried by and extending across the legs of one of the U-shaped members, and the other of said U-shaped members having a slot in its legs for receiving said pin, an overhanging portion on one supporting member for engagement with the other supporting member, said portion having a slot through which the end of the other supporting member may extend, the relationship of the pin and said first named slot being such that when the U-shaped members are axially moved toward each other the adjacent ends of the U-shaped members overlap each other to the extent that pivotal movement of the U-shaped members about the pin is prevented by the overhanging portion of one of the U-shaped members, whereby the supporting members are pivotally joined together while permitting

limited axial movement relative to each other of the supporting members when in horizontal alignment.

3. A foldable garment hanger comprising a pair of inverted U-shaped arms the end of one of which fits within the end of the other, means for pivoting the fitted ends together, a hook forming in part the means for pivoting the fitted ends together, a pair of inverted U-shaped members of lesser cross-sectional dimensions than the dimensions of said arms having their ends pivotally connected together and with their opposite ends pivotally joined with the free ends of said arms, and means for locking the said members in horizontal alignment, said means comprising a pin carried by and extending across the legs of one of the U-shaped members, and the other of said U-shaped members having a slot in its legs for receiving said pin, an overhanging portion on one supporting member for engagement with the other supporting member, said portion having a slot through which the end of the other supporting member may extend, the relationship of the pin and said first named slot being such that when the U-shaped members are axially moved toward each other the adjacent ends of the U-shaped members overlap each other to the extent that pivotal movement of the U-shaped members about the pin is prevented by the overhanging portion of one of the U-shaped members whereby the supporting members are pivotally joined together while permitting limited axial movement relative to each other of the supporting members when in horizontal alignment.

4. A foldable garment hanger comprising a pair of inverted U-shaped arms the end of one of which fits within the end of the other, means for pivoting the fitted ends together, a hook forming in part the means for pivoting the fitted ends together, said hook being pivoted to permit

it to be folded back against the U-shaped arms, a pair of inverted U-shaped members of lesser cross-sectional dimensions than the dimensions of said arms having their ends pivotally connected together and with their opposite ends pivotally joined with the free ends of said arms, and means for locking the said members in horizontal alignment, said means comprising a pin carried by and extending across the legs of one of the U-shaped members, and the other of said U-shaped members having a slot in its legs for receiving said pin, an overhanging portion on one supporting member for engagement with the other supporting member, said portion having a slot through which the end of the other supporting member may extend, the relationship of the pin and said first named slot being such that when the U-shaped members are axially moved toward each other the adjacent ends of the U-shaped members overlap each other to the extent that pivotal movement of the U-shaped members about the pin is prevented by the overhanging portion of one of the U-shaped members whereby the supporting members are pivotally joined together while permitting limited axial movement relative to each other of the supporting members when in horizontal alignment.
